UNITED STATES PATENT OFFICE.

NOBLE HENNINGSSEN, OF SALEM, OREGON.

GASOLINE-DISPENSING STAND.

Application filed August 15, 1922. Serial No. 582,063.

This invention relates to gasoline dispensing tanks, the primary object of the invention being to provide means for dispensing gasoline by the gravity system, eliminating the necessity of using pumps or the like for dispensing fluid from a tank of this character.

Another object of the invention is to provide a dispensing tank of this character wherein the purchaser may at a glance, determine the quantity of gasoline being dispensed by the tank.

A still further object of the invention is to provide means to insure the exact quantity of fluid desired passing from the tank, and obviating any possibility of an excessive quantity of fluid being dispensed.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a front elevational view of a dispensing tank constructed in accordance with the invention.

Figure 2 is a sectional view taken on line 2-2 of Figure 1.

Figure 3 is a sectional view taken on line 3-3 of Figure 2.

Figure 4 is a sectional view taken on line 4-4 of Figure 2.

Figure 5 is an enlarged detail view of the gauge, forming a part of the invention, and Figure 6 is a sectional view through the three-way valve for controlling the passage of fluid through the gauge.

Referring to the drawings in detail, the reference character 5 designates the base of the tank which is formed with the usual opening 6 to permit of access to the interior of the base. Supported at the upper end of the base, is a supporting section 7 on which the tank 8, is mounted.

Secured within the tank 8, and disposed at the upper extremity thereof, is a supporting member 9 providing a support for the guide rod 10 disposed substantially centrally of the tank 8. The base 11 of the tank 8 is formed with a threaded opening to receive the pipe 12 which is relatively

large and provides a support for the movable dispensing tube 13 that operates in the tank 8. This dispensing tube 13 is mounted on the upper end of the controlling rod 14, which rod is formed with a bore formed throughout a portion of its length to accommodate the rod 10 as shown by Figure 2 of the drawings to guide the controlling rod and tube 13 in their movements within the tank.

Positioned in the pipe 12 and contacting with the tube 13 is a suitable stuffing box indicated at 15 which stuffing box provides a fluid-tight connection between the tube 13 and pipe 12, but at the same time permits the tube 12 to be moved within the tank 8, to accomplish its purpose.

A pipe 16 has its upper end secured within the pipe 12 and provides a chamber at the base of the tank 8, which chamber is normally filled with gasoline and may be drawn off by means of the valve 17 to fill small containers such as quart cans or the like. This valve 17 may also be used as a drain to carry off any sediment that may be present in the pipe 16. A stuffing box 18 is supported at the base of the pipe 16 and provides a fluid-tight connection between the walls of the opening at the base of the pipe 16 and the controlling rod 14, which is shown as passing through the opening formed in the lower end of the pipe 16. Each end of the tube 13 is cut away to define a spider 19, which spiders provide spaces to admit fluid to the tube 13, the upper spider also forming a guide for the rod 10.

The discharge pipe to which the filling hose is connected, is indicated at 20, and has connection with the pipe 12 to direct fluid contained in the pipe 12 to the filling hose not shown, where the same may be directed to the tank being filled. The reference character 21 designates a gauge which has its upper end secured within the head 22 which is secured to the wall of the tank 8, in a manner to provide communication between the interior thereof and the gauge.

The lower end of the gauge is supported by the coupling 23 which is secured to the supporting section 7, and has communication with the interior of tank 8 through the pipes 24 and 25, the passage of fluid through the pipes 24 and 25 being regulated by means of the three-way valve 26, a detail view of which is shown by Figure 6 of the drawings.

As shown, the three-way valve 26 has communication with the drain pipe 27 as through the pipe 28, whereby the fluid in the gauge 21 may be drained therefrom and returned to the main or supply tank, not shown.

Fluid is fed into the tank 8 through the pipe 29 that has connection with the main or supply tank not shown, and has its discharge end extended downwardly as at 30, so that fluid enters the tank 8 at the base thereof. Secured to the head 22 and coupling 23, are rods 31 that support the wire mesh material 32 acting as a guard to protect the gauge. The wire mesh material also provides a support for the wire 33 which extends through the wire mesh material crossing the same at predetermined points throughout the length thereof to indicate quantities of fluid contained in the tank 8. In order that the fluid in the pipe 16 and tank 8 may be returned to the supply tank, a valve member 34 is provided, which may be moved to establish communication between the pipe 16 and pipe 27.

Positioned within the base 5 is a rod 35 on which are provided lugs 36, arranged in spaced relation with each other throughout the length of the rod 35. These lugs provide stops or rests for the finger 37 that is carried by the controlling rod 14 so that the controlling rod may be moved to cause the finger to rest on certain lugs regulating the quantity of fluid passing from the tank 8.

The base 5 also provides a cabinet for the dispensing of lubricating oils, a plurality of spigots being indicated at 38, which spigots are in communication with supply tanks not shown. Positioned in the base 5 is a tray 39 which is formed with partitions dividing the tray into a number of compartments, it being understood that a compartment is formed directly under each of the spigots to catch the oil drippings from each spigot.

From the foregoing it will be seen that the tank 8 is filled with gasoline through the pipe 29, and assuming that it is desired to dispense five gallons of gasoline from the tank 8, the finger 37 together with the rod 14,

is moved to a position to bring the finger into engagement with the fifth lug 36, lowering the discharge tube 13 within the tank 8 to a position wherein the gasoline contained in the upper portion of the tank will be drawn off through the discharge pipe 20.

It is contemplated that as soon as a quantity of gasoline has been dispensed, the tank 8 may again be filled ready for the next dispensing operation.

Having thus described the invention, what is claimed as new is:—

1. In a liquid measuring and dispensing device, a casing, a reservoir mounted on top of the casing, a supply pipe rising through the casing and into the reservoir, an overflow pipe extending downwardly from the reservoir through the casing, a measuring tube adjustably mounted through the top of the casing to project into the reservoir to different heights and carry off predetermined quantities of liquid therefrom, a well in the casing surrounding the lower end of said measuring tube, and a drain connection between the lower end of said well and said overflow pipe whereby said reservoir, measuring tube, well and overflow pipe may be entirely drained of liquid when said drain connection is opened and when said measuring tube is lowered in the well.

2. In a gasoline dispensing stand, a base, a tank supported in the upper portion of the base, a discharge pipe mounted in the base and communicating with the tank, a vertically movable dispensing tube operating through the discharge pipe, a drain pipe extending into the tank, a pipe establishing communication between the lower end of the discharge pipe and drain pipe, a valve in the last mentioned pipe to permit fluid to be drained therefrom, and means for adjusting the dispensing tube within the discharge pipe.

In testimony that I claim the foregoing as my own, I have hereto affixed my signature.

NOBLE HENNINGSEN.
